TYPEBAR CONTROL GUIDE

Scott J. Longrod, Ithaca, N.Y., assignor to
SCM Corporation

Filed Dec. 26, 1972, Ser. No. 317,907

Term of patent 14 years

Int. Cl. D18—01

U.S. Cl. D64—11 A

FIG. 1

FIG. 2

FIG. 3

FIG. 4

FIG. 1 is a front perspective view of a typebar control guide for a typewriter showing my new design;

FIG. 2 is a top plan view;

FIG. 3 is a left side elevational view;

FIG. 4 is a rear elevational view.

I claim:

The ornamental design for a typebar control guide, as shown.
